(57) CLAIM

The ornamental design for a beauty valise, as shown and described.

DESCRIPTION

FIG. 1 is a front, perspective view of a beauty valise, showing our new design;

FIG. 2 is a front elevation view of the beauty valise shown in FIG. 1;

FIG. 3 is a rear elevation view of the beauty valise shown in FIG. 1;

FIG. 4 is a left side view of the beauty valise shown in FIG. 1;

FIG. 5 is a right side view of the beauty valise shown in FIG. 1;

FIG. 6 is a top plan view of the beauty valise shown in FIG. 1;

FIG. 7 is a front, perspective view of the beauty valise shown in FIG. 1, shown in an open configuration of use; and, FIG. 8 is a rear, perspective view of the beauty valise shown in FIG. 1, shown in an open configuration of use.

In the drawings, the broken lines illustrate portions of the article which form no part of the claimed design.

1 Claim, 8 Drawing Sheets
